UNITED STATES PATENT OFFICE

CURT HILSCHER, OF CHEMNITZ, GERMANY

CIRCULAR KNITTING MACHINE

Application filed September 13, 1926, Serial No. 135,231, and in Germany February 19, 1926.

The present invention relates to an improvement in circular knitting machines more particularly adapted for the production of a complete stocking having characteristics of a full fashioned stocking. One object thereof has been to provide a machine with which a fashioned stocking of improved quality may be produced automatically with loops of uniform size on a single circular machine, as compared to well known methods whereby full fashioned hosiery is commonly made on two flat machines, namely, a legger and a footer, or whereby seamless stockings are made on a circular machine with fullness of the leg portion produced by loose knitting or large loops and with snugness of the ankle portion produced by tight knitting or small loops.

In some respects the stocking made by the use of my improved apparatus is similar to that illustrated and described in United States patent to Bosworth No. 1,459,497. One important difference is that the stocking made according to my invention is produced without the floating yarns which occur in the Bosworth stocking in the production of the heel portions and the toe portions of Figure 2 thereof.

A machine embodying my invention involves chiefly various improvements over the circular knitting machines of well known types, such, for example, as that shown and described in Bosworth No. 1,149,714. One feature of my invention relates to the novel construction and arrangement of the needles, cams, pickers and control devices therefor whereby I am able to make on a circular machine a full fashioned stocking having the characteristic narrowing and widening in the toe portion and narrowing and widening in the heel portion without producing floating yarns. In this respect, the product of my machine resembles more closely the product of the typical flat hosiery frame, but with the advantage in my machine that the stocking blank is readily produced in a single continuous operation on one machine.

Further features of my invention relate to a novel form of narrowing finger and to novel means for actuating and controlling the knit-

ting cams in such a way as to eliminate some of the difficulties heretofore experienced in attempting to produce full fashioned hosiery on a circular machine.

A preferred embodiment of my invention will be better understood by reference to the drawings accompanying the present specification and in which—

Figure 1 is a view showing an interior development of the knitting cams, needle butts and needle positioning devices arranged in the relative positions which they occupy at the beginning of knitting of the raveling courses preliminary to the knitting of the toe portion of the stocking blank;

Figure 2, a view similar to Figure 1 but showing the relative positions of the parts during knitting of the toe of a stocking;

Figure 3, a similar view showing the relative positions of the parts during knitting of the heel pieces of a stocking;

Figure 4, a similar view showing the relative positions of the parts after knitting of the ankle portion and with the group 1 needles in position to be successively brought into operation to form the widened calf portion.

Figure 5, a similar view showing the relative positions of the parts at the end of the last course of knitting of the calf portion of the leg of a stocking and at the end of a movement of the needle cylinder toward the right;

Figure 22, a detail side view of the widening finger shown in Figures 13, 14 and 18;

65 Figure 23, a rear elevation of a machine embodying the details of construction shown in the preceding figures;

Figure 24, a side elevation of the machine shown in Figure 23; and

Figure 25, a top plan view of the machine shown in Figures 23 and 24.

The article to be produced on my improved circular knitting machine is a stocking comprising a toe portion, a foot, two heel portions, an ankle portion, a calf portion, and the upper leg portion. As shown in Figures 19 and 20, all of these portions except the upper leg portion are formed initially as a divided or, in effect, flat fabric having selvage edges which are later sewed together to form the completed stocking. However, the upper leg portion, being knitted during circular motion of the machine, is tubular and therefore requires no subsequent seaming operation.

My improved circular knitting machine comprises in general a needle cylinder, as 44, Figure 11, provided with the four groups of needles 1, 2, 2' and 3, positioned substantially as indicated in Figure 6. This cylinder is actuated by any suitable well known mechanism for the purpose, not shown, either to rotate continuously in one direction or to reciprocate in accordance with well known circular knitting machine construction, depending upon the part of the stocking to be knitted at any given time. In my improved machine, during knitting of the toe, foot, heel, ankle and calf, the needle cylinder reciprocates; and on each reciprocation, moves through a complete revolution plus an over-run in excess thereof aggregating, in the illustrated machine, five fourths revolutions, or 450°. During knitting of the upper leg portion, the needle cylinder rotates continuously in one direction.

The needles of group 1, Figures 6 and 21, have relatively high butts, those of group 3 have low butts, and the needles in groups 2 and 2' have butts of medium height. It will be noted that the needles of group 3 also have large terminal butts α the purpose of which will be later explained in connection with the positioning of the needles 3 prior to knitting of the heel pieces.

My improved machine is also provided with the usual work or knitting cams 4, 5, 6 and 7 arranged in conventional relation to the path of the needle butts. Also, as indicated in Figures 1 to 5 inclusive, I provide additional needle positioning cams 8, 9, 10, 11, 12, 13 and 14, the several functions of which will be more specifically set forth.

The moving of needles 1 to inoperative position in relation to the work cams at the last quarter or over-run of each course in the knitting of the calf portion is conveniently effected by means of needle lifters 18 and 18', Figure 5, mounted on carriers or slides 17 and 17', Figures 7 and 16, and cooperating with a cam 16 on the needle cylinder 44 in a manner and for a purpose to

be explained in connection with a description of the formation of said calf portion.

My improved machine includes narrowing fingers 34 and 34', Figures 10 and 11, which are operated in a special manner during narrowing of the heel pieces of the stocking.

I also provide a widening finger 76, Figures 13, 14, 18 and 22, having a specially shaped terminal portion presenting different butt engaging steps 74 and 75 and cooperating with actuating means adapted to bring said widening finger into and out of operation in proper relation to the needles, one of said steps, as 74, being adapted to engage a single needle of group 1, during widening of the calf, and the other of said steps, as 75, being adapted to engage two needles of groups 2 and 2' during heel piece widening.

In so far as the devices thus far identified require to be moved into and out of operative position in relation to the needle butts, I effect the desired results in part by means including a pattern drum 29 having a normal surface upon which is mounted a plurality of wedges or wedge shaped cams each of which is positioned in relation to other instrumentalities and adapted to produce a predetermined effect at a predetermined time or at predetermined intervals. The pattern drum is a well known expedient in this as well as other arts for controlling or effecting periodic changes.

In my machine, the drum 29 is utilized in a novel manner to effect changes in the arrangement of or to adjust the parts for producing or knitting different portions of the stocking. I also provide additional control mechanism including a cam disc 35, Figures 10 and 11, for example, whereby at certain parts of the knitting I control or effect periodically repeated changes in the actuation of parts of the knitting instrumentalities during each reciprocating movement of the needle cylinder. Thus, as will be more fully explained, the narrowing fingers 34 and 34' have a special butt actuating movement effected by means of cams 36 mounted on said cam disc 35. Similarly, the widening finger 76 has a special butt actuating movement effected by means of cams 77 also mounted on said cam disc 35, Figure 13. A further special control other than that from drum 29 is illustrated in Figure 12 wherein I show cam sectors 51 and 52 on the needle cylinder 44 which control the operation of thread guides 48 and 48' during knitting of the heel portions on needle groups 2 and 2', also to be described in greater detail.

Another special control or change mechanism is shown in Figures 9 and 9a. As illustrated therein, a sector 24 imparts reciprocatory motion to the needle cylinder 44 and cooperates with said cylinder and with the usual driving mechanism in a well known manner; but it is also utilized in my machine

to effect to-and-from movement of the working cams to intermittently prevent them from engaging and actuating certain of the needles during reciprocating movement of the needle cylinder.

Having enumerated the more important and distinctive parts of my improved circular knitting machine, I will now explain the operation thereof by describing in sequence the knitting of the different portions of a stocking blank, for example, such as that shown in Figure 19.

Knitting the toe courses

The toe of the stocking shown in Figure 19 is knitted on the needles of group 3 during reciprocating motion of needle cylinder 44 and while the needles of groups 2, 2' and 1 remain inoperative. According to known practice, a few raveling courses are formed prior to the knitting of the toe courses proper, after which the usual narrowing and widening to form the toe pocket takes place by operation of the well known instrumentalities for such purpose. However, during reciprocating motion, the needle cylinder has an overrun, i. e. moves through five-fourths revolutions or 450° in each direction; and, unless some means were employed to prevent it, the butts of needles 3 would be carried twice across the knitting cams in each direction of motion of said cylinder. Accordingly, I mount the working cams 4, 5, 6 and 7 on the cam carrier or slider 23, Figure 9, which is periodically withdrawn from butt engaging or extended position during the over-run, or approximately the last 90° of movement of the needle cylinder in each direction, except while knitting the calf portion, during which operation a different device is employed for a similar purpose.

As shown in Figures 9 and 10, slider 23 is engaged by the upper or free end of lever 30, the lower end of which carries a cam roller 26 slidably mounted thereon and thus adjustable vertically into and out of the path of cams 25 and 25' on the reciprocating rocking sector 24. In the drawings, the roller 26 is shown out of operative position, or as it is when the machine is in circular operation. However, when reciprocating knitting begins, i. e. at the first raveling course on needles of groups 3, 2 and 2', for example, the cam 31 on pattern drum 29 moves out from under the forward end 33 of lever 27 pivoted at 27' which is depressed toward the drum by spring 32, Fig. 23. The consequent upward thrust of the rear end of lever 27 is transmitted through link 28 to roller 26 which is normally spring pressed toward inoperative position. This upward thrust of link 28 moves and maintains the roller 26 in the path of cams 25 and 25', so that, with reciprocation of the sector 24, roller 26 rides alternately on said cams through the last 90°

of rotation of the needle cylinder in each direction and until cam 31 again moves under the end of lever 27. Said cam is positioned and timed to return roller 26 into inoperative or lowered position just before the needles of group 1 are moved successively into operative knitting position by the widening finger, as hereinafter described in connection with knitting of the calf portion.

10 *Knitting the foot portion*

When the toe has been knitted, the cam 11, Figure 2, is moved inwardly toward the needle cylinder by well known means operating from the pattern drum 29, of the type shown in Figure 8 for actuating cam 14, for example, so that the butts of the needles 2 and 2' may be engaged and lowered by said cam into knitting position. The foot is then produced, during continued reciprocating motion of the needle cylinder, on the needle groups 3, 2 and 2', group 3 carrying the upper or instep part of the foot while groups 2 and 2' knit at sides of said upper part and the 25 divided sole portion with selvage edges.

Knitting the heel pieces

Referring again to Bosworth's Patent No. 1,459,497, it will be noted that in the stocking forms illustrated in Figures 2 and 3, the heel portions are formed with floating yarns. The disadvantages incident thereto are well understood; and one purpose of my invention has been to provide a machine in which the heel pieces are knitted without producing floating yarns.

Accordingly, upon completion of the foot and instep portion, the needles of group 3 upon which said instep portion has been 10 knitted as above described, are shifted or raised to inoperative position but retain the last formed instep loops while the heel pieces are knitted. Meanwhile, the needle groups 2 and 2' at either side of group 3 continue 15 in operation to knit the two heel pieces with narrowing and widening, to form a heel when the edges of said heel pieces are later sewed together. Suitable means for automatically shifting the group 3 needles upwardly or into 20 inoperative position include the cam 14, Figures 3, 8 and 15, which is spring pressed inwardly towards the needle cylinder 44 to engage the lower butts α of said needles. Inasmuch as each reciprocation of the needle cylinder covers five-fourths revolutions or 450° , it will be apparent that with cam 14 in operative position, a single turn of the needle cylinder is sufficient to engage and displace all of 25 the group 3 needles into inoperative position, whereupon said cam is retracted to inoperative position.

To actuate the needle positioning cam 14, cam 54 on pattern drum 29 moves into engagement with the lower end 62 of a lever 55, pivoted at 55a, Figure 8, which, through a

link 57, lever 56, pivoted at 56a, another link 58 and a lever 59, pivoted at 59a, deflects a wedge shaped cam 63 on the free end of said lever 59 into engagement with a transverse notch in the side of a spring pressed slide rod 61 upon the inner end of which the cam 14 is mounted. A spring 114 cooperating with said rod 61 tends to press said cam normally toward needle butt engaging position. The wedge or cam 54 is shaped and disposed to engage the end 62 of lever 55 to hold cam 14 normally out of needle butt engaging position and, when disengaged or withdrawn, to permit forward movement of cam 14 only for the purpose above described; namely, to move the 80 instep needles out of knitting position in preparation for knitting the heel pieces.

Unless some special means were provided at this juncture to prevent it, the reciprocatory motion of the needle cylinder in the formation of the separated heel pieces would normally produce the undesirable floating yarns above referred to. To avoid this, the two thread guides 48 and 48', Figure 11, are positioned and adapted to supply thread separately to the needle groups 2 and 2' while knitting the heel pieces. These thread guides 48 and 48' operate alternately by cooperating with oscillating levers 49 and 49' of different lengths and which are actuated by two cams in the form of ring sectors 51 and 52 secured at different heights on the usual sinker ring of the needle cylinder 44 and having overlapping portions. The longer of said levers 49 and 49' is adapted to be engaged by the lower ring sector 52 while the shorter is adapted to be engaged by the upper ring sector 51, the arrangement being such that when lever 49, for example, rides on its ring sector, its lower end moves outwardly and the upper end deflects the corresponding thread guide 48 to non-feeding position, or in such a way that the thread carried thereby is not delivered to the needles as they pass. Thus, although both groups of needles pass both thread guides at each reciprocation, yarn is fed by each guide only to one group and in such manner that no threads or yarns are floated. The change from operation of one guide to operation of the other in each course occurs when the space 53, Figure 12, comes opposite the tails or lower ends of both levers 49 and 49'. And when both of said levers engage the overlapping portions of their respective cams, both thread guides are out of action. This occurs while needles 3 are passing said guides.

The knitting of the heel pocket, or rather of the heel pieces forming the heel pocket, involves a narrowing operation followed by a widening operation. For the narrowing, I provide two narrowing fingers 34 and 34', Figure 10, which are positioned and mounted to successively raise the required number of needles of each of groups 2 and 2' into inop-

erative position, beginning at the needles *b* and *b'* respectively, Figure 6. In this operation, the problem is to actuate the narrowing fingers in such a manner that they operate during movement of the needle cylinder in the counter clockwise direction to engage a needle butt at point *b*, without engaging a butt at the point *a'*; and during movement in the opposite direction to engage a needle butt at point *b'* and not at *a*.

Accordingly, the narrowing fingers are lifted out of butt engaging position, Figure 11, during each reciprocation of the needle cylinder when the needles at points *a* and *a'* respectively pass the fingers 34 and 34'. This particular control of the movement of narrowing fingers 34 and 34' is effected by means including cams 36 mounted on a cam disc 35 and cooperating with a cam roller or follower 47 mounted on a rod 43, one end of which is secured to a slide bar 37 which is provided with notches 46 and 46' in its forward edge, i. e. toward the needle cylinder. During rotation of the cam disc 35, endwise sliding movement is imparted to the slide bar 37. As indicated in Figure 11, the slide bar 37 is positioned to engage and deflect levers 38 pivotally mounted at 38' and held in yielding engagement with the forward edge of said slide bar by springs 45. At the free ends of levers 38, I provide adjustable lugs 138, the outer ends of which engage the tail pieces of the fingers 34 and 34' respectively.

Accordingly, while the cam follower 47 is riding on one of the cams 36, Figure 10, the free ends of levers 38 engage the forward edge of slide bar 37 thus holding the lugs 138 in forward position and deflecting the fingers 34, 34' into the inoperative position indicated in Figure 11. However, when, upon further rotation of the cam disc 35, the cam roller rides into the gap or depression between the cams 36, the slide bar 37 is retracted endwise, thus permitting the free ends of the spring pressed levers 38 to deflect rearwardly into the notches 46 and 46', whereupon the fingers 34 and 34', by reason of the usual spring pressed actuating arrangement thereof are deflected downwardly or into operative needle butt engaging position or that in which the narrowing fingers effect narrowing beginning at the points *b* and *b'*, Figure 6.

Obviously, the cams 36 are so proportioned and related, and the cam disc 35 is so actuated from the driving mechanism, that the described operation of the narrowing fingers 34 and 34' is timed to occur in proper sequence during each reciprocating movement of the needle cylinder 44. This operation is distinct and separate from a further control provided to arrest the intermittent deflection of the narrowing devices into and out of their normal operative position.

For the latter purpose, the pattern or control drum 29, Fig. 24, is equipped with a wedge or cam 42, positioned to move under the lower end of a lever 40 which, through link 41 deflects the arm of lever 39 and thus moves the roller 47 which is mounted also on lever 39 to a position out of engagement with the cam 36 and the cam disc 35.

Widening of the heel pieces by widening fingers 76 hereinafter more particularly described in connection with knitting of the calf portion takes place in the reverse order to that of the narrowing, and continues until the heel pieces are completed and the knitting again reaches the line of loops representing the last course of the instep, whereupon the ankle portion of the stocking is knitted on groups 3, 2 and 2'.

Knitting the ankle portion

It will be recalled that just before beginning knitting of the heel pieces, the needles of group 3 were raised out of operative position by cam 14 where they remained during the knitting of said heel pieces and with the last formed loops of the instep portion suspended on them. These needles 3 are now returned to active knitting position by the cam 11 and the formation of the ankle or lower leg portion on said needles and those of groups 2 and 2' continues with normal reciprocating movement of the needle cylinder until it becomes necessary to make changes for knitting of the calf portion.

Knitting the calf portion

Knitting of the ankle, as above indicated, involved the operation of needle groups 2, 2' and 3. Knitting of the calf portion with gradual widening effect necessitates bringing in gradually or successively the needles of group 1 which have up to this point remained inoperative. Accordingly, cams 12 and 13 are, at this point, moved into operative butt engaging position and intercept the butts of needles 1 to raise them into the position shown in Figure 4, or such that their butts pass above the cams 8 and 9 as well as above the working cams. It will be understood that the above described movement occurs because the butts of group 1 needles are the longest; and cam 12 is moved inwardly just enough to engage these butts, but not enough to engage the butts of the remaining needles.

When the butts of needles 1 are raised as in Figure 4, they are in position to be engaged and acted upon by the widening finger 76 controlled and actuated in such a manner as to produce a gradual widening in the formation of the calf portion. In the previously described widening of heel and toe portions, widening finger 76 brought two needles simultaneously into operative position on each side of the fabric in accordance with well understood practice. However, when knit

ting the calf of the stocking, it is desirable to widen more gradually, so that only one needle is added at a time to the row of working needles on each side of the fabric. Thereafter, several courses of loops are knitted before another new needle is added. Accordingly, under some circumstances, it is desirable to add one needle i. e. when widening the calf, and under other circumstances it is desirable to add two, as when widening the heel.

I provide a single widening finger 76 adapted for adding either one needle or two needles at will. For this purpose, and as indicated in Figures 18 and 22, the butt engaging portion of said widening finger 76, instead of presenting the usual uniform surface of known forms of fingers, is provided with portions or steps 74 and 75 of different size, Figure 22. The step 74 is of a shape and size adapted to the widening requirements of the heel and toe, or in other words, such that two needle butts are engaged by the finger. However, the very high butts of needles 1 for knitting the edges of the calf portion, as above indicated, do not engage the surface of step 74 but ride only upon the surface or step 75 which is so small that only one needle butt can be operatively engaged thereby. In this manner, a single needle of group 1 is displaced at each widening operation on needles 1 in the formation of the calf portion by the same finger 76 as is utilized in the regular widening of the toe and heel.

To permit the more gradual widening of the calf portion, that is, by adding one needle of group 1 and then knitting several courses without adding a needle, I provide a special widening finger control mechanism adapted to be operated at or during knitting of the calf. As indicated in Figures 13 and 14, the finger 76 is mounted in the path of a lever arm 81 adapted to be deflected periodically by suitable means including cams 77 mounted on the cam disc 35. A cam follower or roller 78 is positioned to engage said cams and the spaces between said cams, thus imparting rocking motion to a lever 79 which is in turn imparted through a link 80 to the lever 81. In accordance with this arrangement, the parts are so timed that the widening finger 76 is deflected out of operative position in relation to the needle butts of needles in group 1 over any predetermined number of courses, during which period the reciprocating motion of the needle cylinder continues and normal knitting is effected without addition of needles to the knitting row. The inoperative position of finger 76 is indicated in dotted lines in Figure 13 just below the operative position, shown in full lines.

It has been previously noted that the needle cylinder of my improved machine is arranged to execute reciprocating movement with an over-run of approximately 90° in each direc-

tion. When knitting of the stocking reaches the point or course where the needles in group 1 are required to function, as in knitting the calf portion, I provide means to avoid the repeated engagement of the working cams 70 with the needles 1 during each reciprocating motion of the needle cylinder, as by displacing said needles during the over-run or last quarter revolution of the needle cylinder to a position above the path of the working cams 75 4, 5, 6 and 7.

For this purpose, at either side of said working cams 4, 5, 6 and 7, slides or needle lifter carriers 17 and 17', Figure 5, are mounted to be moved radially toward and away from the needle cylinder. Needle lifters 18 and 18', pivotally mounted on said slides are actuated by levers 19 and 19', respectively, pivoted at *d* and *d'*, respectively, on said slides 17 and 17'. Links 20 and 21', respectively, each having a slot near one end, operatively connect said levers 19 and 19' with the lifters 18 and 18', respectively. A cam 16, Figures 5 and 17, mounted on the needle cylinder approximately below the middle needle of group 1, moves with the cylinder, and in so doing, engages levers 19 and 19' in both directions of movement of said cylinder.

In operation, when the needle cylinder rotates to the left, cam 16 strikes the side *f* of lever 19 which is deflected and in turn deflects the arm 67 which transmits endwise movement to link 20 and thence to the needle lifter 18. This is timed to occur when the leading needle of group 1, during the over-run of each cylinder oscillation, reaches the path of the lifter which thereupon deflects said needle and the following needles in group 1 to inoperative position above the working cam 7 so that they do not work, i. e. engage the working cams a second time, in that course.

When the lifter 18 reaches its operative or raised position, Figure 5, a detent at the end of a spring 21 engages a notch *n* in the tail of the lifter to hold it there until reverse oscillation of the needle cylinder causes disengagement of said spring from the notch *n*. The parts now occupy the relative positions shown in Figure 5. When the needle cylinder reverses, i. e. rotates toward the right, the needles of group 1, previously raised by the lifter 18 in the last 90° of rotation, are lowered by the cam 8 into operative position to normally engage the knitting cams, and cam 16 engages the lever 19 from the side *h* and, through link 20 moves the needle lifter 18 down to its lowest or inoperative position. Thereafter when the needle cylinder has moved through a whole revolution to the right, the cam 16 strikes the depending lever 19' from the side *f'* so that the following needles of group 1 during the last quarter revolution are again raised above the working cam 7 as previously stated. Upon the next

movement of rotation of the needle cylinder toward the left, the lifted needles are lowered into the working position by the cam 9. The cycle of operations hereinabove described is repeated during knitting of the calf portion.

The needle lifter carriers or slides 17 and 17' are controlled as shown more clearly in Figures 7 and 16, the latter illustrating the operative position of slide 17 during knitting of the calf portion. Upon completion thereof, and for the purpose of withdrawing said slide and the needle lifters 18 and 18', from operative position, I provide suitable slide actuating mechanism cooperating with drum 29 and including a wedge or cam 64 mounted thereon and positioned to engage the lower end 66 of lever 65, the outer end of which moves the link 67 and thereby lever 68 secured on a rock shaft 72 journaled in bearings 70. The outer end of shaft 72, Figure 16, carries a lever 69, the upper or free end of which pulls against an extension or abutment 71 of the slide 17 and moves the latter outwardly to inoperative position against tension of spring 73 which tends normally to move slide 17 into operative position.

It will be understood that, during knitting of the calf the working cams on slide 23 remain in their forward or knitting position and are not periodically moved in and out, for the purposes previously set forth in the description of other operations involving over-run of the needle cylinder in excess of a complete revolution in each direction.

As soon as the widening of the calf portion has progressed until all of needles 1 have been brought into action, reciprocating motion of the needle cylinder is discontinued, and circular motion thereof begins and continues over the predetermined number of courses required to form the upper leg portion of the stocking, this operation being in no wise different from regular circular knitting.

As will be well understood, the last circular course may be knocked over, thus completing the stocking blank; or, a portion thereof may be knocked over and a succeeding stocking blank may be started as a continuation of the fabric of the preceding stocking just completed. This being the preferred method, I will now describe the changes whereby the transition is made from the completed stocking to the beginning of the toe portion of a new stocking in the manner previously described.

Upon completion of the last course of circular knitting, cam 10, Figure 1, is pushed in sufficiently to engage the butts of needles 1, namely, those with the high butts. These needles are moved downwardly out of knitting or operative position; but needles 2, 2' and 3 would still continue to knit except that cam 12 is now pushed inwardly toward

the needle cylinder to engage the butts of needles 2 and 2' whereby the latter are displaced to the position shown in Figure 2, namely, above the knitting cams 4, 5, 6 and 7. The needles are now arranged so that only those of group 3 remain with their butts in position to engage the knitting cams to knit the toe portion during reciprocating motion of the needle cylinder and in the manner previously described. Thereupon, the previously described operations are repeated to produce the next complete stocking blank, and as many thereof as may be required.

I claim:

1. A circular knitting machine for producing a complete stocking, comprising in combination a rotatable needle bed, needles in said needle bed arranged in several groups, the heels of said needles being of different heights according to the group to which the needles belong, means for making said needle bed execute alternately an oscillating and a circular movement in accordance with the desired manner of knitting, cams for operating the heels of the different needles, a regulating drum, wedges on said drum, levers and links for operating said cams from said drum, two slides, and two oscillatable needle lifters oscillating in accordance with the speed at which the circumference of said needle bed rotates, and means for adjusting said slides radially to said needle bed to bring into the operative position those needles which at the oscillating movement of the needle bed at the knitting of the calf would come twice into the range of the working cam.

2. A circular knitting machine for producing a complete stocking, comprising in combination a rotatable needle bed, needles in said needle bed arranged in several groups, the heels of said needles being of different heights according to the group to which the needles belong, means for making said needle bed execute alternately an oscillating and a circular movement in accordance with the desired manner of knitting, cams for operating the heels of the different needles, a regulating drum, wedges on said drum, levers and links for operating said cams from said drum, two slides, and two oscillatable needle lifters oscillating in accordance with the speed at which the circumference of said needle bed rotates, and means for adjusting said slides radially to said needle bed to bring into the operative position those needles which at the oscillating movement of the needle bed at the knitting of the calf would come twice into the range of the working cam, and a double widening finger of such construction that at the increasing of the number of operative needles in toe and heel two needles at a time are brought into the working position by said widening finger.

whilst at the knitting of the calf only one needle is brought into the working position by the same widening finger.

3. A circular knitting machine for producing a complete stocking, comprising in combination a rotatable needle bed, needles in said needle bed arranged in several groups, the heels of said needles being of different heights according to the group to which the needles belong, means for making said needle bed execute alternately an oscillating and a circular movement in accordance with the desired manner of knitting, cams for operating the heels of the different needles, a regulating drum, wedges on said drum, levers and links for operating said cams from said drum, two slides, and two oscillatable needle lifters oscillating in accordance with the speed at which the circumference of said needle bed rotates, and means for adjusting said slides radially to said needle bed to bring into the operative position those needles which at the oscillating movement of the needle bed at the knitting of the calf would come twice into the range of the working cam, and a double widening finger of such construction that at the increasing of the number of operative needles in toe and heel two needles at a time are brought into the working position by said widening finger whilst at the knitting of the calf only one needle is brought into the working position by the same widening finger, and means for bringing said widening finger periodically into the inoperative position so that after every four rows it brings one needle at each side of the first needle group into the working position.

4. A circular knitting machine for producing a complete stocking, comprising in combination a rotatable needle bed, needles in said needle bed arranged in several groups, the heels of said needles being of different heights according to the group to which the needles belong, means for making said needle bed execute alternately an oscillating and a circular movement in accordance with the desired manner of knitting, cams for operating the heels of the different needles, a regulating drum, wedges on said drum, levers and links for operating said cams from said drum, two slides, and two oscillatable needle lifters oscillating in accordance with the speed at which the circumference of said needle bed rotates, and means for adjusting said slides radially to said needle bed to bring into the operative position those needles which at the oscillating movement of the needle bed at the knitting of the calf would come twice into the range of the working cam, and a double widening finger of such construction that at the increasing of the number of operative needles in toe and heel two needles at a time are brought into the working position by said widening finger

whilst at the knitting of the calf only one needle is brought into the working position by the same widening finger, and means for bringing said widening finger periodically into the inoperative position so that after every four rows it brings one needle at each side of the first needle group into the working position by said working cam into the working position at the knitting of the calf.

In testimony whereof I affix my signature.
CURT HILSCHER.
